Rosemount Field Mount Flow Meter Transmitter, posted on emerson.com, no posted date given, no production date given, [online], [site visited Mar. 20, 2018], Available from Internet, URL: <http://www.emerson.com/en-us/catalog/automation-solutions/measurement-instrumentation/flow/rosemount-8732e> (Year: 2018).*

Primary Examiner — Garth Rademaker*Assistant Examiner* — Fitzgerald L Butac(74) *Attorney, Agent, or Firm* — Stetina Brunda Garred and Brucker; Mark B. Garred(57) **CLAIM**

The ornamental design for a flowmeter, as shown and described.

DESCRIPTION

FIG. 1 is a front elevational view of the flowmeter of the present invention showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a bottom, front perspective view thereof; and,

FIG. 8 is a top, rear perspective view thereof.

The broken lines show portions of a flowmeter that from no part of the claimed design.
